UNITED STATES PATENT OFFICE.

EDWARD D. BRONSON AND MOSES W. DILLINGHAM, OF AMSTERDAM, N. Y.

IMPROVEMENT IN BROOMS.

Specification forming part of Letters Patent No. 129,926, dated July 30, 1872.

To all whom it may concern:

Be it known that we, EDWARD D. BRONSON and MOSES W. DILLINGHAM, of Amsterdam, in the county of Montgomery and State of New York, have invented a new and valuable Improvement in Brooms; and we do hereby declare that the following is a full, clear, and exact description of the construction and operation of the same, reference being had to the annexed drawing making a part of this specification, and to the letters and figures of reference marked thereon.

Figure 1 of the drawing is a representation of a side view of my invention. Fig. 2 is a perspective view of the cap and ribs.

This invention has relation to the manufacture of brooms; and consists in the combination of the metallic cap or collar which encircles the handle and covers the shank with fluted or studded ribs, designed to hold the strands of wire by which the shank is fastened to the handle, and in the method of winding and securing the wire, whereby a broom of great strength and durability is produced.

Referring to the accompanying drawing, A represents the metallic cap or collar, bell-shaped, as shown, and secured to the handle of the broom by means of rivets or other suitable fastenings. This cap covers the end of the shank C, and is provided with the vertical or side ribs D, which embrace the sides of the shank, and are fluted or studded to provide recesses for the reception of the strands of wire E, which are wound around the shank in spiral order, as shown. These ribs may be properly struck up in dies and afterward soldered to the cap, or the cap and ribs may be struck up together.

My method of winding the wire is as follows: First, I secure the lower end of the wire to the lower end of the handle by means of a tack or rivet, and then, after arranging the corn as evenly as the first stage of the process requires, pass the wire through an opening at a to the outside of the shank. I now wrap the wire around the base of the shank several times, as shown at b, and then lay back the

corn sufficiently to obtain access to the handle, after which I carry the wire thereto through an opening at a', and wrap or wind the same spirally around the handle until the point b¹ is reached. I next pass it through an opening at b¹ and form the external coils b³, after which I again turn back the corn and rewind the wire around the handle until the last strand is brought as high up as the wire needs to be—that is, near the upper end of the shank. I next raise that part of the corn which I previously bent over, and which is to constitute the shank, to its proper position, and pass the wire to the outside through a suitable opening. At this point I apply the cap and ribs, first cutting the ends of the corn evenly, and then finish the process by wrapping the wire around the outside of the shank and within the recesses of the ribs, and fasten it at c by a tack or rivet. This arrangement of the wire renders it less liable to loosen or to come out if it should break at any point than when arranged according to the ordinary method. The broom may be quickly wired and at a saving of material. Sometimes one of the external coils b b³ may be dispensed with altogether at the first stage of the process and finished after the wire is wrapped around the ribs. The process of winding the wire may be advantageously adopted in cases where the cap and ribs are dispensed with.

What we claim as our invention, and desire to secure by Letters Patent, is—

1. The combination of the cap A and fluted or studded ribs D, substantially as specified.
2. The combination, with the cap A and ribs D, of the wire E, applied substantially as described.

In testimony that we claim the above we have hereunto subscribed our names in the presence of two witnesses.

EDWARD D. BRONSON.
MOSES W. DILLINGHAM.
